W. H. WINEMAN

PNEUMATIC HAMMER

Filed Oct. 26, 1918

UNITED STATES PATENT OFFICE.

WADE H. WINEMAN, OF CHICAGO, ILLINOIS, ASSIGNOR TO SULLIVAN MACHINERY COMPANY, A CORPORATION OF MASSACHUSETTS.

PNEUMATIC HAMMER.

Application filed October 26, 1918. Serial No. 259,789.

To all whom it may concern:

Be it known that I, WADE H. WINEMAN, a citizen of the United States, residing at Chicago, in the county of Cook and State 5 of Illinois, have invented certain new and useful Improvements in Pneumatic Hammers, of which the following is a full, clear, and exact specification.

This invention relates to pneumatic hammers, and more particularly to the pneumatic hammers used in drill sharpeners for operating the upper swaging die, the object 10 of the present invention being to provide a means for controlling the hammer and a mechanism operably attached to the hammer controlling means for normally holding the upper swaging die in an elevated position. In a type of drill sharpener now extensively used, the swaging dies are placed 15 substantially in alinement with the upsetting mechanism, necessitating the holding of the upper die in an elevated position to permit a clearance between the dies so that the upsetting mechanism is readily accessible to 20 the operator. It is one of the objects of this invention to provide an automatically acting mechanism for retaining the dies separated so that while working the steel the operator 25 may change from the swaging to the upsetting operation without having to perform the intermediate operation of separating the dies and inserting some means for holding 30 the dies separated. These and other objects and advantages of my improved construction will hereinafter more fully appear.

In the accompanying drawings, I have for purposes of illustration shown one embodiment which my invention may assume in practice.

40 In these drawings,—

Fig. 1 is a front elevation of a drill sharpener embodying my invention.

Fig. 2 is a side elevation of the die operating mechanism.

45 Fig. 3 is a longitudinal sectional view of the inlet valve.

Fig. 4 is an enlarged end view of the upper rock shaft and the controlling means attached thereto.

50 Fig. 5 is a vertical central section through the cylinder and valve mechanism of the die operating motor.

Referring to the drawing and to the machine shown therein, while the invention

may be embodied in machines and devices 55 other than the specific type herein shown, for the sake of illustration there is shown one embodiment of the invention in a drill sharpener 1, having a base 2 on which is secured a lower swaging die 3. Bolted to the 60 base at 4 is an upright support 5 for supporting in a vertical position a pneumatic hammer 6 for operating the upper swaging die 7. The upper swaging die 7 reciprocates in a 65 vertical guide 8 formed integral with the support 5.

A foot lever 9 is attached to one end of a rocker shaft 10, passing through the base 2, the other end of the rocker shaft carrying a lever 11 for actuating a vertically disposed 70 rod 12 which controls a valve mechanism and a die holding mechanism in a manner to be hereinafter described. A spring 13 is held under partial compression between a flange on the support 5 and a collar on the 75 valve rod, to normally hold the valve rod in an elevated position.

The upper swaging die is reciprocated by 80 a piston rod 14 carried on the lower end of a piston, adapted to reciprocate in a cylinder 15 of a pneumatic hammer 6. A valve chamber 16 is mounted on the side of the hammer 6 and encloses a valve for directing the flow of pressure fluid alternately to the opposite ends of the piston in a manner well 85 known in the art.

The flow of pressure fluid from any suitable source, as a pressure tank, through a pipe 17 to the valve chamber 16, is controlled by a normally closed valve mounted 90 adjacent the valve chamber. This valve comprises a casing 18 provided with internally threaded, oppositely disposed portions 19 whereby the same may be connected to the pipe 17 and to a short pipe 20 leading to the 95 valve chamber 16. A partition 21 divides the valve casing 18 into two substantially equal parts and carries substantially centrally of the casing a valve seat 22. A projection 23 is cast on the lower side of the 100 casing 18 and is provided with external threads, or other suitable means, whereby a boss 24 is secured in alinement therewith. Also mounted on the valve casing 18, but diametrically opposite the externally threaded 105 projection 23, is an internally threaded collar 25 adapted to receive a screw plug 26 provided with a cylindrical recess 27 pass-

ing part way through the plug and opening into the valve chamber. Holes are provided centrally of the members 23 and 24 and in alignment with the valve seat 22 and recess 5 27 to receive a valve pin 28 and a valve actuating rod 29, the latter being provided with a head 30 adapted to contact with the valve pin 28. A valve member 31 is mounted on the valve pin near the upper end thereof 10 and is normally held in contact with the valve seat 22 by a spring 32 which abuts against the valve member and screw plug 26 and which is held in position by the upper end of the valve pin which passes centrally 15 through the spring.

Journalized in bearings secured to the support 5 is a second rock shaft 33 provided at one end with an arm 34 operatively connected by means of a lost motion connection 35 20 with the valve controlled rod 12 through a link 36, the rock shaft being further provided at its other end with an eccentrically mounted pin 37, carrying one end of the valve actuating rod 29. As shown, this rod 25 29 is made in two parts, the upper part being threaded into the lower and being held against relative movement therewith by a lock nut 29'. This construction permits of an adjustment in the length of the rod so 30 that the different members may be adjusted to preserve their proper relation and to permit the valve to seat.

Intermediate the ends of the rock shaft and rigidly secured thereto is a dog or pawl 38 adapted to rest in a depression in the upper die 7 in such a manner that it holds the die against downward movement. The weight of the valve actuating rod 29 normally tends to rotate the rock shaft counter-clockwise to bring the pawl against the swaging die so it will fall into the depression formed therein. The lost motion connection permits the rocker shaft to rotate independently of the valve control rod 12, so that 40 when the swaging die moves upwardly and strikes the pawl the rocker shaft will rotate sufficiently to permit the pawl to slide over the edge of the die and fall into the depression, as has been described. A third rocker 45 shaft 39 rotatably mounted in a projection 40 formed on the hammer or its support, is actuated by an arm 41 rigidly connected to the shaft and connected by a pin to the upper end of the control rod 12. The other end of 50 this rocker shaft carries a lever 42 in which is a depression for receiving one end of a pin 43 which passes upward through the lower head of the valve chest 16. When the rod 12 is raised, this pin 43 forces the hammer controlling valve in the valve chest 16 into its extreme raised position, so as to direct a flow of pressure fluid to the under side of the piston to force the piston upward and temporarily hold it elevated.

60 When the operator desires to use the

swaging mechanism, he depresses the foot lever 9 which operates the control rod 12 and causes the link to rotate the rocker shaft 33 in a clockwise direction and so frees the upper die by raising the pawl from contact therewith and also opens the valve 18 to permit a flow of pressure fluid to the hammer to actuate the piston. The downward movement of the control rod rotates the rocker shaft 39 in a clockwise direction 75 to permit the pin 43 to fall so that the valve in the chest 16 can perform its normal functions.

When the operator removes his foot from the lever 9, the control rod is forced upward, the lost motion connection breaks the control on the rocker shaft 33, which rotates counter-clockwise under the weight of the valve actuating rod 29, and so brings the pawl 38 into the path of the reciprocating die. The rocker shaft 39 is rotated in a counter-clockwise direction to force the pin 43 upward so that the fluid pressure may act on the lower side of the piston to raise the swaging die. By this means the proper elevation of the die is ensured so that the pawl 38 may fall in the depression formed in the die block. In order to make the operation clearer it may be repeated in more detail, it being understood that the mode of operation of the device is one of such nature that several events occur in a specific time relation.

Let it be assumed that the hammer has been operating, that the pawl 38 is moved out of the path of the die 7, that the plunger 43 is moved beyond the path of travel of the distributing valve in the valve chest 16, and that the valve 31 is unseated. The sequence of events in stopping the hammer will be as follows: As the operator's foot is removed from the pedal 9 and the rod 12 moves upwardly, the member 42 forces the plunger 43 into engagement with the valve and so discontinues the reciprocation of the piston which operates the die 7 and brings the die to raised position. As this is accomplished, the pawl 38 which has been released drops into the notch in the side of the die 7, which it can readily do by reason of the raised position of the die, and simultaneously the valve 31 finally cuts off pressure supply and so closes down the hammer. It will be noted from Fig. 4, in which the position of the parts is that corresponding to a time when the pawl is held out of the notch in the die 7 and when the hammer is operating, that the pin 37, which determines the position of the valve 31 by means of the plungers 29 and 28, is nearly in line between the axis of the rock shaft 33 and the valve 31. It will therefore be noted that, as the arm 34 moves upwardly, the valve 31 will be closed at first only very gradually and that accordingly while there will be a throttling of the supply of air to 130

the hammer, the air will not be shut off until after ample opportunity has been given for the shifting of the distributing valve to the position to raise the die. It will be further noted that by reason of the presence of the slot indicated at 35, the engagement of the top of the die 7 with the member 38 will cause a momentary reopening of the valve 31 whereby to effect the admission of a final small quantity of fluid to carry through the upward motion of the piston and die 7 without releasing the distributing valve from its raised position. Thus it is seen that I have devised a simple and efficient means for normally retaining the upper swaging die in an elevated position, and means for causing the die holding mechanism to operate when the fluid pressure is cut off from the pneumatic hammer which operates the die.

While I have herein shown and described, for the purpose of illustration, one specific form of the invention, it is to be understood that the same has been shown for illustrative purposes only and that extensive deviations may be made from the disclosed form thereof without departing from the spirit of the invention.

What I claim as new and desire to secure by Letters Patent is:

- 30 1. In a drill sharpener, the combination with swaging means comprising stationary and movable dies and a fluid pressure motor for actuating said movable die, of controlling means for said motor operative to cause raising of said die prior to the shutting down of said motor, and automatic mechanical means adapted to engage said die and hold it in raised position, said controlling means being operative to entirely discontinue supply of fluid pressure to said motor when said die is held stationary in raised position.
- 40 2. In a drill sharpener, the combination with swaging means comprising stationary and movable dies and a fluid pressure motor for actuating said movable die, of control means for said sharpener comprising a valve adapted to control the supply of pressure fluid to said motor, mechanical means normally extending into the path of said movable die and operative when so extended to hold said die in raised position, and control mechanism for said valve and said mechanical means operative in one position to open said valve and withdraw said holding means and in another position to permit said holding means to extend into the path of said movable die and said valve to close, said control mechanism including a mechanical interconnection whereby said valve may be momentarily opened upon engagement of said holding means by said die upon upward movement of the latter.
- 50 3. In a drill sharpener, the combination of swaging means comprising stationary and movable dies and a fluid pressure motor for actuating said movable die, of control means for said sharpener comprising a valve adapted to control the supply of pressure fluid to said motor, mechanical means normally extending into the path of said movable die and operative when so extended to hold said die in raised position, and control mechanism for said valve and said mechanical means operative in one position to open said valve and withdraw said holding means and in another position to permit said holding means to extend into the path of said movable die and said valve to close, said control mechanism including a mechanical interconnection whereby said valve may be momentarily opened upon engagement of said holding means by said die upon upward movement of the latter.
- 60 4. In a drill sharpener, the combination with swaging means comprising stationary and movable dies and a fluid pressure motor for actuating said movable die, of control means for said sharpener comprising a valve adapted to control the supply of pressure fluid to said motor, mechanical means normally extending into the path of said movable die and operative when so extended to hold said die in raised position, and control mechanism for said valve and said mechanical means operative in one position to open said valve and withdraw said holding means and in another position to permit said holding means to extend into the path of said movable die and said valve to close, said control mechanism including a mechanical interconnection whereby said valve may be momentarily opened upon engagement of said holding means by said die upon upward movement of the latter.
- 70 5. In an apparatus of the character set forth, coacting die means, a motor for operating the same, means for supplying motive fluid under pressure to the motor, means for distributing said motive fluid therein to repeatedly actuate said motor, means to control said second mentioned means to maintain one of said die members in one position, mechanical means coacting therewith to lock said die in said position, and common control means having a lost motion connection with said last mentioned means and controlling the operation of all of said means.
- 80 6. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said
- 90 7. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said
- 100 8. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said
- 110 9. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said
- 120 10. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said
- 130 11. In an apparatus of the character set forth, coacting die means, a motor having a piston for operating the same, means for controlling the supplying of motive fluid under pressure to the motor and for distributing it therein to cause said motor piston to be repeatedly actuated to cause repeated relative movements of said dies, mechanical means operable to maintain one of said die members in one position, and controlling means for said several means operative to effect movement of said die to said

position, operation of said mechanical means to hold it therein, and interruption of the fluid supply to the motor.

7. In an apparatus of the character set forth, coacting die means, a motor having a piston for operating one of the same, means for controlling the supplying of motive fluid under pressure to the motor and for distributing it therein to cause said motor piston to be repeatedly actuated, mechanical means operable to maintain one of said die members in one position, and common controlling means for said several means operative in fixed sequence on actuation thereof to effect movement of said die to said position, operation of said mechanical means to hold it therein, and interruption of the fluid supply to the motor.

8. In an apparatus of the character set forth, an anvil, a movable hammer cooperating therewith, means including a fluid pressure actuated piston for causing said hammer to strike a work piece on said anvil a series of blows, means for controlling the supply of fluid to said piston, means for mechanically holding said hammer in elevated position, and controlling means for said two last mentioned means operative on actuation automatically to cause said piston to raise said hammer, to cause said holding means to engage the same, and to interrupt fluid supply to said piston. 20 25 30

In testimony whereof I affix my signature.

WADE H. WINEMAN.
